UNITED STATES PATENT OFFICE.

BENJAMIN F. GUEST, OF SOUTH BETHLEHEM, PENNSYLVANIA, ASSIGNOR TO STOKES AND SMITH COMPANY, OF PHILADELPHIA, PENNSYLVANIA, A CORPORATION OF PENNSYLVANIA.

SHEET-FEEDING APPARATUS.

Application filed January 31, 1925. Serial No. 5,950.

My invention relates to apparatus for feeding or withdrawing sheets, as of paper or other material, one at a time from a pile or stack thereof, to any suitable destination, 5 as to a coating machine which may thereafter apply to the sheet a coating of fluid, as adhesive, wax or the like.

It is the object of my invention to overcome the tendency of neighboring sheets in 10 the pile or stack to adhere or otherwise stick to each other, as in the case where the sheets are embossed, or have upon their surfaces materials inducing more or less adhesion, or where the sheets stick to each other at their 15 edges, particularly the edges of notches, as a result of a cutting operation in their formation, or in the case where the sheets have formed in them registering perforations, to ensure that the feeding mechanism will with- 20 draw from a stack or pile a single sheet only.

To this end there is provided in the feeding apparatus a roller which by suction picks up a sheet, preferably adjacent its edge, lifting the edge free from the stack and there- 25 upon directing into the gap between the separated sheet and the stack a blast of fluid, as air, which passes between the selected sheet and the stack throughout the adjacent faces thereof effectively to separate the sheet from 30 the stack.

My invention resides in apparatus of the character hereinafter described and claimed.

For an illustration of one of the various forms my invention may take, reference is 35 had to the accompanying drawing, in which Figure 1 is a side elevational view, partly in vertical section, of mechanism embodying my invention.

Figure 2 is a partial side elevation.

Upon a table or support 1, vertically mov- 40 able upon and with respect to the frame 2, is disposed a stack S, of sheets, as of paper or the like, and more particularly labels or box covers to be delivered to adhesive-applying means in advance of the application of the labels or covers to boxes. At its rear edge the stack S is confined by a back stop 8, and at its forward or right end abuts against the upper portion of the frame member 2, upon 45 which is disposed the holder member 3 carrying, when suitable or desirable, the holder member 4, which are preferably yielding or resilient, and which may be bristle brushes.

The suction roller 5 is provided as usual 50 with the bore 6, with which there is perma-

nently in communication the pipe or tube 7 connected through the suction breaking valve V with the vacuum or exhaust pump 8. In its periphery the roller 5 is provided with the cup or recess 9 in communication through 60 the passage 10 with the bore 6.

The support or bar 12 is moved forwardly and backwardly by the rock shaft 11 through mechanical connections, including the oscillating lever 33, carrying therewith the idler 65 feed roll 13, co-acting with the driven feed roller 14, and the tongue or guide member 15. The suction roll 5 is moved upwardly and backwardly, to the right and to the left, above the stack S by an arm 34 connected thereto 70 and pivoted to the bracket 35 extending upwardly from carriage 12. To effect desirable partial rotation of roll 5, the shaft thereof is journaled in the ends of arm 34, and rollers, not shown, on the ends of the shaft travel 75 along a path defined by the inclined guideway or bracket 36. The aforesaid movements of rolls 5 and 13, tongue 15 and support 12 and the structure effecting it is more fully disclosed in Nitsch and Baker appli- 80 cation, Serial Number 3,316, filed January 19, 1925. Tongue 15 has a nozzle or passage 16 with which communicates the pipe or tube 17 communicating at its other end with the interior of the valve member 19 rotatable 85 within the valve casing member 18. The valve member 19 is oscillated by the rock shaft 11 through the rock lever 20, pivoted connecting link 21 and arm 22, the last named connected to the valve member 19. 90 There is delivered through the pipe or conduit 23 air or other suitable fluid under pressure from any suitable source, as a separate air-forcing pump; or, as in the example illus- 95 trated, the exhaust of the pump 8. In the example illustrated, the exhaust of the pump 8 communicates with the chamber 24, in which may be disposed air-filtering material 25, and which may communicate with the atmosphere through the valve or cock 26, and 100 which delivers air under pressure to the aforesaid passage 23.

The valve member 19 is provided with the bore or passage 27 with which the tube 17 is permanently in communication. Commu- 105 nicating with the bore 27 are the three pas- sages 28, 29 and 30. In the valve casing 18 is a port 31 with which the conduit 23 com- municates, and a second port 32 open to the atmosphere.

The operation is as follows:

In the position of the suction roller 5 indicated, the valve V is closed to atmosphere, with resultant application of suction to the recess or cup 9, causing the uppermost sheet to be sucked upwardly and away from the stack S into engagement with the roller 5, which in moving rearwardly rotates in counter-clockwise direction, lifting the forward 10 end of the sheet clear from the stack. At the same time the member 12 has been moved rearwardly, toward the left, bringing the tongue or guide member 15 to a position to the left of the forward edge of the sheet 15 which has lately been removed from the stack. Thereupon the valve V opens to atmosphere, by engagement of tappet member 37 with the stem of valve V as effected by the bar 38 reciprocable with the carriage or member 20 12, cutting off the suction from the cup 9 and thereby releasing the selected sheet, whose forward end then falls upon the guide surface 15^a of the tongue 15. Upon discontinuance of the suction and release of the 25 sheet to fall upon the member 15, the valve member 19 comes to such position that the passage 29 comes into communication with the port 31, whereupon air under pressure passes through the tube 17 and the nozzle 16 30 and is delivered as a jet into the space between the now separate sheet and the stack, the rapidly moving air passing rearwardly or to the left between the separate sheet and the stack S, stripping or completely separating 35 the selected sheet from the stack and permitting its subsequent feeding by the rolls 13 and 14, which are now substantially in contact with each other. Upon the return movement of the member 12 and roller 5 to 40 the extreme forward position illustrated, the valve V is again closed, and the valve member 19 rotated to the position indicated, whereupon the air pressure upon the nozzle 16 is discontinued and the exhaust from the 45 pump 8 passes to atmosphere through the ports 30 and 32.

Suitably to adjust the pressure of the air upon the nozzle 16, the opening of the cock 26 to atmosphere may be adjusted; for increasing the pressure upon the nozzle 16 the opening of the cock 26 is decreased.

For the sake of brevity in the appended claims, the term "air" includes air and any other suitable fluid.

What I claim is:

1. Apparatus for feeding sheets from a stack thereof comprising means for picking a sheet from the compacted stack, a sheet-moving member for receiving the sheet and 50 having a passage, and means for delivering air through said passage between the sheet and compacted stack to separate them.

2. Apparatus for feeding sheets from a stack thereof comprising means for picking

a sheet from the stack, a sheet-moving member for receiving the sheet and having a passage, and means for delivering air through said passage after the sheet has been picked from the stack to separate the sheet from the stack. 65

3. Apparatus for feeding sheets from a stack thereof comprising means for picking a sheet from the stack, a guide member for receiving the sheet movable with respect to the stack and having a passage, and means for delivering air through said passage between the sheet and stack to separate them. 70

4. Apparatus for feeding sheets from a stack thereof comprising means for picking a sheet from the compacted stack, a guide member for receiving the sheet movable with respect to the stack to receive the sheet, said guide member having a passage, and means for delivering air through said passage while the sheet is upon said guide member for separating the sheet from the compacted stack. 80

5. Apparatus for feeding sheets from a stack thereof comprising a suction roll for moving a portion of a sheet from the compacted stack, a guide member movable with respect to the stack for receiving the sheet and having a passage, and means for delivering air through said passage between the sheet and compacted stack for separating them. 90

6. Apparatus for feeding sheets from a stack thereof comprising a suction roll for moving a portion of a sheet from the compacted stack, a guide member movable with respect to the stack for receiving the sheet and having a passage, and an air pump whose intake is connected with said suction roll for delivering air through said passage between the sheet and compacted stack to separate them. 100

7. Apparatus for feeding sheets from a stack thereof comprising means for raising a portion of a sheet from the stack, a movable guide member for receiving said portion of the sheet and having a passage, and means operative after predetermined movement of said guide member for delivering air through said passage between the sheet and the stack to separate them. 110

8. Apparatus for feeding sheets from a stack thereof comprising means for picking a sheet from the stack, a guide member for receiving the sheet and having a passage, means for releasing the sheet from said picking means during movement of said guide member, and means for thereafter delivering air through said passage for separating the sheet from the stack. 115

9. Apparatus for feeding sheets from a stack thereof comprising means for picking a sheet from the stack, a guide member for receiving the sheet and having a passage, means for releasing the sheet from said pick- 125

ing means, and means for thereafter delivering air through said passage for separating the sheet from the stack.

10. Apparatus for feeding sheets from a stack thereof comprising a suction roll rotatable about its own axis for removing a portion of the sheet from the stack, and a guide member for receiving the sheet comprising means for delivering air between the sheet and stack for separating them.

11. The combination with apparatus for feeding sheets from a stack thereof comprising means for picking a sheet from the stack adjacent an edge thereof, a member movable

to effect further separation of said sheet from 15 said stack having a passage, and means for delivering air through said passage during movement of said member.

12. The combination with apparatus for feeding sheets from a stack thereof comprising means for picking a sheet from the stack adjacent an edge thereof, a wedge-shaped member movable to effect further separation of said sheet from said stack having a passage adjacent its entering edge, and means 25 for delivering air through said passage during movement of said member.
